UNITED STATES PATENT OFFICE.

HENRY L. DOANE, OF RUSHTON, MICHIGAN.

TIRE-REMOVER.

SPECIFICATION forming part of Letters Patent No. 741,891, dated October 20, 1903.

Application filed March 4, 1903. Serial No. 146,181. (No model.)

To all whom it may concern:

Be it known that I, HENRY L. DOANE, a citizen of the United States, residing at Rushton, in the county of Livingston and State of Michigan, have invented certain new and useful Improvements in Tire-Removers, of which the following is a specification, reference being had therein to the accompanying drawings.

The invention relates to a novel type of mechanism for removing tires from vehicle-wheels; and it consists in the peculiar and simple construction of a tire-remover and in various details of construction, as will be more fully hereinafter described, and shown in the drawings, in which—

Figure 1 is a vertical section through my improved tire-remover, and Fig. 2 is a front elevation thereof.

In construction the device comprises a vertical supporting-frame A, consisting of the side members A' and A², the latter member being of considerably greater length than the side A', and a top or connecting member A³. The lower end of the side A² is adapted to engage the felly of the wheel and to rest thereon in the manner hereinafter set forth. The supporting-frame is strengthened by means of diagonal braces A⁴, which connect the sides.

D represents a threaded shaft or screw which extends loosely through an opening a in the top of the supporting-frame and projects below the side A' a considerable distance. The screw is provided with a head D', in which is inserted the operating-lever D². A collar or bearing member D³ is also formed upon or otherwise secured to the screw and is adapted to bear against the frame-top during the operation of the device.

E designates a cross-head threaded upon the lower end of the screw and having vertical openings b formed therein upon each side of its center.

G represents a tire-engaging device in the form of a framework detachably connected to the head E and carrying means adapted to engage the lower edge of the tire. The frame is composed of rods c, the upper ends of which are threaded and project through the opening in the cross-head E. Nuts d are provided for the rod ends. The lower portions of the rods are connected by a cross member or foot

H, adapted to bear against the lower edge of the wheel-tire I.

J designates a guide in the form of a U-shaped bar for holding the tire-engaging frame in proper position. Parallel members e of the guide extend through the side A² of the supporting-frame and are provided with nuts f.

The tire-remover is applied to the wheel in the manner indicated in Fig. 1, the wheel being secured upon a suitable support J' and held in place by the clamp J². The lug or side member A² of the supporting-frame rests upon the wheel-felly, while the foot H engages the lower edge of the tire. By operating the screw through the agency of its lever a vertical movement of the foot is effected relative to the supporting-frame and the tire thus detached. The device is adapted to be moved along the wheel to different portions of its rim during the removing of the tire and is held in a vertical position on the wheel by a chain K, the chain ends being attached to the clamp J² and a hook g on the supporting-frame. By using a chain in the manner set forth means are provided for maintaining the tire-remover in a vertical position upon wheels of different diameters.

From the description of the invention it will be obvious that the tire-remover is of simple construction and the parts are so assembled as to be readily detached when desired, so that the device will occupy a minimum amount of space for storage or transportation.

What I claim as my invention is—

1. In a tire-remover, the combination with a vertical supporting-frame having a side member shaped at its lower end to engage the wheel-felly, of a screw extending loosely through the frame-top and carrying a bearing member engaging said top, a head threaded upon the lower end of the screw and detachable therefrom, a tire-engaging device carried by the head and projecting below and in operative relation to the frame, and a lever for operating the screw.

2. In a tire-remover, the combination with a vertical supporting-frame having one of its sides shaped to engage and rest upon the wheel-felly, of a screw extending loosely

through an opening formed in the frame-top, a collar rigidly secured to the screw adapted to bear against said top, a cross-head threaded upon the screw and detachable therefrom, 5 rods detachably connected to the head and projecting below the supporting-frame, a cross bar or foot connecting the lower ends of the rods and adapted to engage the lower edge of the tire, and a lever for operating the screw.

10 3. In a tire-remover, the combination with the vertical supporting-frame having one of its sides shaped to engage and rest upon the wheel-felly, of a screw extending loosely

through an opening in the frame-top, and carrying a bearing member engaging said top, 15 a head threaded upon the lower end of the screw, a tire-engaging device detachably connected to the head, a guide upon the supporting-frame for the tire-engaging device, and a lever for operating the screw.

In testimony whereof I affix my signature in presence of two witnesses.

HENRY L. DOANE.
